CLAIM

The ornamental design for a woman's shoe, as shown and described.

DESCRIPTION

FIG. 1 is a perspective view of a woman's shoe showing our new design;

FIG. 2 is a front end view thereof;

FIG. 3 is a back end view thereof;

FIG. 4 is a left side view thereof;

FIG. 5 is a right side view thereof;

FIG. 6 is a top plan view thereof; and,

FIG. 7 is a bottom plan view thereof.

The broken line showing of the tread and sole of the shoe is included for the purpose of illustrating environmental structure and forms no part of the claimed design.

1 Claim, 6 Drawing Sheets
